MACHINE TOOL BASE AND BED UNIT

Harry E. Miles, Jr., 6 W. Hannum Blvd.,
Saginaw, Mich. 48602

Original design application Apr. 30, 1964, Ser. No.
79,759, now Patent No. 204,207, dated Mar. 29, 1966.
Divided and this application Feb. 25, 1966, Ser. No.
1,189

Term of patent 14 years

(Cl. D55—1)

FIGURE 1 is a front perspective view of a machine tool base and bed unit showing my new design;

FIGURE 2 is a side elevation thereof, the opposite end being a mirror image thereof;

FIGURE 3 is a rear elevation thereof;

FIGURE 4 is a front elevation thereof; and

FIGURE 5 is a top plan view thereof.

The broken lines representing a hydraulic power unit and work supporting table in FIGURE 2 is shown for illustrative purposes only.

This is a division of design application Serial No. D.79,759, filed April 30, 1964, and now Patent No. D.204,207.

I claim:

The ornamental design for a machine tool base and bed unit, as shown and described.
